UNITED STATES PATENT OFFICE

157,109

TOASTER

Chauncey E. Waltman, Chicago, Ill., assignor to
Dominion Electric Corporation, a corporation
of Ohio

Application June 17, 1949, Serial No. 3,380

Term of patent 14 years

(Cl. D81—10)

To all whom it may concern:

Be it known that I, Chauncey E. Waltman, a citizen of the United States, residing in the city of Chicago, county of Cook, and State of Illinois, have invented a new, original, and ornamental Design for a Toaster, of which the following is a specification, reference being had to the accompanying drawing forming a part thereof:

Figure 1 is a top plan view of a toaster showing my new design;

Figure 2 is a side elevational view thereof;

Figure 3 is an end elevational view looking at the right end thereof as viewed in Figure 1;

Figure 4 is an end elevational view looking at the left end thereof as viewed in Figure 1.

I claim:

The ornamental design for a toaster, substantially as shown.

CHAUNCEY E. WALTMAN.
